UNITED STATES PATENT OFFICE.

PHILIPP GOLDMANN, OF NEW YORK, N. Y.

CAP.

SPECIFICATION forming part of Letters Patent No. 230,770, dated August 3, 1880.

Application filed June 23, 1880. (No model.)

To all whom it may concern:

Be it known that I, PHILIPP GOLDMANN, a citizen of the German Empire, residing at New York, in the county and State of New York, 5 have invented new and useful Improvements in Caps, of which the following is a specification.

This invention consists in the combination, with a cap or hat having a flexible crown, of 10 a tip or lining comprising a side part of hair-cloth or other like material, a top part, and a spring or reed at the junction of such two parts for the purpose of supporting the crown both in a vertical and horizontal direction.

15 This invention is illustrated in the accompanying drawings, in which—

Figure 1 shows it applied to a cap. Fig. 2 is a cross-section of a portion of the crown on a larger scale than in the previous figure.

20 Similar letters of reference indicate like parts.

The letter A designates the crown, and B the tip or lining, comprising a side part, b, a top part, d, and a reed or spring, a.

25 The crown A is made of a flexible material, as cloth, and in this example the article of which it forms a part is what is known as a "fatigue-cap" for Knights Templar. The tip or lining B is fitted into the crown A, and its 30 side part, b, is composed of hair-cloth or other material of a similar nature, while it is stitched to the crown, as at e, Fig. 1, for the purpose of keeping the tip or lining in place.

The top part, d, of the tip or lining is made 35 of buckram, but any other fibrous or textile material may be substituted therefor; and the reed or spring a consists of a strip of whale-bone or other stiff elastic material. This reed or spring a is situated at the junction of the 40 side part, b, with the top part, d, of the tip for lining, and it is held in place by a line of stitches, c, which serve also to connect the

parts b d with each other, the arrangement of these stitches being as follows, viz: The side part, b, is folded and the spring or reed a is 45 laid in its fold. The top part, d, is then bent over the reed-inclosing fold of the side part, and the stitches c are made through the whole, as indicated in Fig. 2.

On the inside of both parts b d of the tip or 50 lining I usually apply a facing of silk or the like.

It will be seen that the reed or spring a forms a support for the crown A in a horizontal direction, while the hair-cloth composing the 55 side part, b, is an effective support thereto in a vertical direction, and hence the crown is kept in shape under all conditions.

I am aware that it is old to combine with a cap or hat a tip having a reed or spring for 60 the purpose of distending or supporting the crown in a vertical direction. Such springs, however, are objectionable on account of their weight and their liability to get out of order, besides showing on the outside of the cap or 65 hat, whereas the hair-cloth composing the side part, b, of my cap or hat is destitute of these objections, and effectually answers the purpose of the spiral springs.

What I claim is—

70 The combination, with a cap or hat having a flexible crown, of a tip or lining comprising a side part of hair-cloth or other like material, a top part, and a spring or reed at the junction of such two parts, substantially as 75 shown and described.

In testimony whereof I have hereunto set my hand and seal in the presence of two subscribing witnesses.

PHILIPP GOLDMANN. [L. S.]
